(57) **CLAIM**

The ornamental design for a LIGHT FIXTURE HOUSING as shown and described.

DESCRIPTION

FIG. 1 is a perspective view of a LIGHT FIXTURE HOUSING embodying the present invention.

FIG. 2 is a left side view of the design shown in FIG. 1.

FIG. 3 is a right side view of the design shown in FIG. 1.

FIG. 4 is a top view of the design shown in FIG. 1.

FIG. 5 is a bottom view of the design shown in FIG. 1.

FIG. 6 is a front view of the design shown in FIG. 1.

FIG. 7 is a rear view of the design shown in FIG. 1.

The broken lines shown in the drawings are included for the purpose of illustrating portions of the LIGHT FIXTURE HOUSING and form no part of the claimed design.

1 Claim, 6 Drawing Sheets

FIG. 3

FIG. 4

FIG. 6**FIG. 7**
